United States Patent Office

Des. 190,840
Patented July 4, 1961

190,840

AIRCRAFT

William P. Lear, Sr., Le Ranche Onex, Geneva,
Switzerland, assignor to Lear, Incorporated

Filed Aug. 26, 1959, Ser. No. 57,318

Term of patent 14 years

(Cl. D71—1)

FIG. 1

FIG. 2

Des. 190,840

PAGE 2

FIG. 3

FIG. 4

FIG. 1 is a top plan view of an airplane showing my new design;

FIG. 2 is an end elevational view thereof;

FIG. 3 is a side elevation of the airplane; and

FIG. 4 is a bottom perspective view thereof, taken from the side opposite that shown in FIG. 3.

I claim:

The ornamental design for aircraft, substantially as shown.
